UNITED STATES PATENT OFFICE.

LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

AIR DISTRIBUTOR FOR LIQUID-FUEL BURNERS.

Application filed June 29, 1922. Serial No. 571,672.

To all whom it may concern:

Be it known that I, LEE S. CHADWICK, a citizen of the United States, residing at Shaker Heights Village, in the county of 5 Cuyahoga and State of Ohio, have invented a certain new and useful Improvement in Air Distributors for Liquid-Fuel Burners, of which the following is a full, clear, and exact description, reference being had to 10 the accompanying drawings.

This invention relates to oil burners, and more particularly to an improved air distributor or so-called flame spreader for use with such burners.

15 Devices similar to that constituting the subject matter of this application are shown in my former applications Serial Nos. 528, 813, 528,814, 528,833 (the last mentioned being a joint application of myself and one 20 Marc Resek), filed January 12, 1922, 541, 898, filed March 8, 1922, and in an application which I am filing concurrently herewith and entitled Air controlling member 25 for oil burners. A construction identical with that herein disclosed is exhibited in an application which I filed March 24, 1922, Serial No. 546,349, and wherein the claims are restricted to a safety feature applicable to variously constructed air distributors 30 for oil burners.

The primary object of the invention is to provide an air distributor through which the power and efficiency of the burner wherewith it is used is increased and the 35 character of the flame improved, the flame, by reason of the even distribution of air effected by the device, being free from objectionable streaks.

Further objects are to provide a construction 40 which renders the distributor very substantial and durable, imparts rigidity to it, facilitates assembly, expedites manufacture, and which so controls and distributes the air that parts of the spreader are 45 protected from the heat of the flame and therefore maintained at a comparatively low temperature.

Other objects will appear as I proceed to 50 describe the invention by reference to the accompanying drawings which illustrate the present preferred embodiment and wherein Fig. 1 represents a central vertical section through the upper portion of an oil burner and through my improved air distributor

wherewith the burner is equipped; Fig. 2 55 is a sectional plan substantially on the line 2-2 of Fig. 1; Fig. 3 is a horizontal section through the burner substantially on the line 3-3 of Fig. 1; and Fig. 4 is a plan view of the burner with the air distributor 60 or flame spreader removed.

The burner wherewith my improved air distributor is designed for use is of the tubular class but it is distinguished from the more common ones of this class by its 65 relatively large size which has acquired for it the name "Giant Burner." The burner includes inner and outer wick tubes 1 and 2, respectively, between which a cylindrical wick 3 is guided, the wick being adapted 70 to be raised and lowered by wick raising means (not shown). A spanner 5 is situated within the upper end of the inner wick tube and is spaced a suitable distance downwardly from the top thereof. This spanner 75 constitutes a support for the air distributor or flame spreader.

Practically all parts of the air distributor or flame spreader are drawn from sheet metal and the same comprises a tubular 80 central structure element 10 which, by reason of its primary function I shall term the lock. This lock is shown as made up of top and bottom sections 11 and 12, respectively, the former having a top wall 85 13 and being flared outwardly at its lower end in two steps, the lower of which constitutes a shoulder 14 from the outer edge of which depends a flange 15. The lower section 12 has its upper end flared outwardly to form a horizontally disposed 90 abutment 16 and then turned upwardly to form a flange 17 which fits within the former flange 15 and below which the edge portion of the latter flange is crimped to clamp 95 the sections firmly together with the edge of the flange 17 against the shoulder 14.

The top of the distributor or flame spreader is designated 20 and it has an aperture which fits over the slightly elevated 100 central portion of the top wall 13 of the lock 10 and is secured to the peripheral portion of said wall by any suitable means, as by rivets 22. The top 20 is formed to provide a cylindrical part 23, a horizontal 105 portion 24 therebelow, a decided dip 25 outwardly beyond the portion 24, and an upwardly bulged part 26 beyond the dip 25.

The upper end of a supporting member or tube 30 fits within the cylindrical part 23 and is secured thereto, as by indentations 31. Secured in a similar manner to the substantial vertical center of the tube 30 is a sleeve 33 which constitutes a part of what is usually termed the flame spreader flange 35. This flange has a horizontal portion 36 spaced a comparatively short distance 10 below the lower edge of the dip 25, and a slightly raised peripheral portion 37 disposed below the bulged portion 26 of the top. The extreme edge portion of the flange is turned abruptly downwardly over 15 the wick space between the tubes 1 and 2 and this portion of the flange may be referred to as the lip 38.

What is known as the body of the air distributor or flame spreader is designated 40 and it comprises a substantially cylindrical wall which is turned inwardly at its upper end, as shown at 41, and is enlarged at its lower end, as shown at 42. The extreme lower edge of this wall occupies a depressed 25 annular bead 43 of a downwardly and inwardly inclined bottom wall 44, said wall being provided outwardly beyond the bead 43 with a flange 45 which embraces and is turned over the upper edge of the enlargement 42 thereby to secure the cylindrical wall and the bottom wall together. The bottom wall terminates at its inner edge in a flange 46 which fits the lower end of the tube 30 and to which it may be secured, as by 35 indentations 47.

A frame 50 is carried by and depends from the spanner 5, and locking elements 51 are pivotally connected at 52 to the frame and have keeper portions 53 which are 40 adapted to be engaged over the abutment 16 of the lock 10 when the locking elements are forced apart by a pin 55 that is slidably supported within the upper end of the lock and which is provided above the top of the distributor or flame spreader with a knob 56, the pin serving as a means for lifting the distributor or flame spreader from the burner as well as an actuator for the locking 45 elements. The locking elements are restrained against undue pivotal movement by stops 57 which project from the top of the frame 50 through openings 58 in said elements. This locking of the flame spreader to the spanner constitutes no part of my present invention but is fully disclosed and claimed in the aforesaid application of myself and Marc Resek, Serial No. 528,833; and the purpose of the frame 50 is set forth in my previously mentioned application Serial 55 No. 528,813.

Extending outwardly and downwardly from beneath the flange 36, toward the lip 38 thereof, is a baffle 60 which is affiliated with perforations 61 in the downwardly 60 turned edge portion of the flange 36 to make

up a safety feature that constitutes the subject matter of my application Serial No. 546,349 above referred to.

The spanner 5 is provided with a large central opening 65 and with a series of segmental openings 66, and throughout the greater portion of its circumference its edge is spaced from the inner wick tube by lugs 67 to provide passageways 68. The lock 10 is open at its lower end, is provided with large openings 70 in substantially the horizontal plane of the space between the flange 36 and the edge portion of the top 20, the openings being separated by supporting bars 71, and the top wall 13 of the lock has a series of relatively small openings 72. The tube 30 has openings 75 in substantially the plane of the openings 70 of the lock, and the last mentioned openings are separated by supporting bars 76. The tube 30 is provided with a second series of openings 77, separated by bars 78, and through which communication is established between the interior of the tube and the interior of the body 40.

Perforations 80 are formed in the bottom wall 44 of the body, and perforations 81, in the peripheral wall thereof a slight distance above the upper edge of the flange 45. The top 20, inwardly of its cylindrical portion 23, has a series of openings 83, and its portions 24 and 26 are provided, respectively, with perforations 84 and 85.

When the burner is in operation, and is associated with the other well known elements which go to make up a complete apparatus, such as the drum and the drum supporting collar, as disclosed in Letters Patent No. 848,828, issued April 2, 1907, to W. R. Jeavons, there is a current of air induced by the heat of the flame upwardly through the inner wick tube. A part of this air rises through the openings of the spanner 5 into the interior of the lock 10 and the tube 30, the greater amount of that rising within the lock passing out through the openings 70 to join that within the tube and to escape with it through the openings 75 and the restricted passageway between the flange 36 and the dip 25 of the top. A certain amount of this air, however, escapes through the perforations 72 in the top wall 13 of the lock; a part through the openings 83 of the top 20, and a part through the perforations 84 and 85 of the respective portions 24 and 26 of the top. The air escaping through the passageway between the flange 36 and the peripheral portion of the top imparts proper shape to the flame and, rising between the flame and the top, protects the latter from the intense heat of the flame. This wall of air, so to speak, is prevented from converging to too great an extent as it rises above the burner by the air which is supplied to the space therewith through the perforations 84 and 85, the openings 83, and the perfora- 125

tions 72, the air issuing through the last mentioned perforations serving further to retain the knob 56 at a relatively low temperature.

5 In order that it may serve its purpose best, the air issuing from between the flange 36 and the peripheral portion of the top must be in a practically unbroken sheet and this is accomplished, notwithstanding voids 10 which may occur in the body of air passing from the interior of the lock 10 and the interior of the tube 30 by reason of the presence of the supporting bars 71 and 76 which tend to divide the body of air into radial 15 streams, by the air being smoothed out into a comparatively thin body as it passes through the restricted passageways between the dip 25 and the horizontal portion of the flange 36 and between the extreme edge portions 20 of the bulged part 26 of the top and the flange portion immediately therebelow. This is held as an important feature of my present invention.

A part of the air rising within the tube 25 30 issues through the openings 77 into the interior of the body 40, and this is augmented by air rising through the perforations 80 of the bottom wall 44. The major part of this air escapes over the upper end of the 35 body and is directed by the deflector 60 downwardly beneath the lip 38 to supply the required oxygen to the flame. The space between the inner side of the wick and the peripheral wall of the body is supplied with air through the perforations 81, and 40 through the passageways 68 about the edge of the spanner 5. The air passing through this space prevents vapors dropping from the wick into said space and also prevents 45 the condensation of any vapors therein, the air passing through the perforations 81 serving especially to prevent condensation within the sheltered area immediately above the enlargement 42 of the body 40.

Attention is directed to the fact that the enlargement of the lock 10, or more specifically the abutment portion 16 thereof, serves as a deflector to direct a proper amount of the air rising within the tube 30 outwardly 50 through the openings 77 thereof.

Having thus described my invention, what I claim is:

1. An air distributor for liquid fuel burners of the character set forth comprising a 55 central structural element, a tube surrounding and spaced from said element, means joining together the upper end of the tube and element, a flame spreader flange carried by the tube and extending outwardly therefrom, a flame spreader body disposed below the flange and surrounding and having connection with the lower end of the tube, the tube having a series of openings in substantially the plane of the body, and the central structural element terminating at its lower 60

end in substantially the plane of the corresponding end of the tube.

2. An air distributor for liquid fuel burners of the character set forth comprising a central structural element, a top secured to the upper end of said element and extending outwardly therefrom, a tube surrounding the structural element and spaced therefrom, said tube depending from the top and situated inwardly of its peripheral portion, 70 a flame spreader flange carried by the tube below and in spaced relation to the peripheral portion of the top, and a flame spreader body disposed below the flange and having a bottom wall through which it has connection with the lower end of the tube, the tube having a series of openings in substantially the transverse plane of the space between the peripheral portion of the top and the flange and a second series of openings in the 75 transverse plane of the body.

3. An air distributor for liquid fuel burners of the character set forth comprising a central structural element, a tube surrounding said element, means joining together and spacing apart the upper ends of the tube and element, a flame spreader flange carried by the tube and extending outwardly therefrom, and a flame spreader body disposed below the flange and having connection with the lower end of the tube, the tube having a 90 series of openings in substantially the transverse plane of the body, the central structural element having a deflecting portion in operative relation to said series of openings.

4. An air distributor for liquid fuel burners of the character set forth comprising a central structural element, a top secured to the upper end of said element and extending outwardly therefrom, a tube depending from the top inwardly of its peripheral portion and outside and spaced from said central structural element, a flame spreader flange carried by the tube below and in spaced relation to the peripheral portion of the top, and a flame spreader body disposed below the flange and having connection with the lower end of the tube, the tube having a series of openings in substantially the transverse plane of the space between the peripheral portion of the top and the flange, and a second series of openings in the transverse plane of the body, the central element having a circumferential enlargement constituting a deflector that is in operative relation to the last mentioned series of openings.

5. An air distributor for liquid fuel burners of the character set forth comprising a central structural element, a top applied to the upper end of said element and extending outwardly therefrom, the top being formed to provide a substantially cylindrical part that is spaced outwardly from said structural element, a tube having its upper end fitted and secured to the cylindrical part of 125 130

- the top and depending therefrom, a flame flange having its inner edge portion secured, a spreader flange secured to and extending to the tube, said flange being spaced a distance outwardly from the tube below and in spaced relation to the peripheral portion of the top, relation to the peripheral portion of the top, top and so shaped and positioned with respect thereto to provide therewith restricted 70 openings in substantially the transverse plane of the tube having a series of openings in the space between the peripheral portion of the top and the flange, the tube having a series of openings in substantially the transverse plane of said tube, and a flame spreader body surrounding the lower end of the tube in spaced relation to the flame spreader flange, and a second series of openings in the transverse plane of the body.
6. An air distributor for liquid fuel burners of the character set forth comprising a central structural element, a top applied to the upper end of said element and extending outwardly, thence downwardly and again outwardly therefrom, to provide a substantially cylindrical part that is spaced from the central structural element, a tube having its upper end fitted within and secured to the cylindrical part of the top and depending therefrom to substantially the plane of the lower end of the central structural element, a flame spreader flange secured to and extending outwardly from the tube below and in spaced relation to the peripheral portion of the top, and a flame spreader body surrounding the lower end of the tube in spaced relation to the flange, the tube having a series of openings in substantially the transverse plane of the space between the peripheral portion of the top and the flange and a second series of openings in the transverse plane of the body.
7. An air distributor for liquid fuel burners of the character set forth comprising a tubular supporting member, two substantially horizontal flange like elements surrounding the supporting member, one above the other, the latter constituting the flame spreader flange, said elements converging then diverging and again approaching each other outwardly from the supporting member to provide a succession of restricted air passageways, and a flame spreader body surrounding the supporting member having a circumferentially disposed series of openings that are separated by supporting parts and are located between the horizontal planes of the aforesaid flange like elements.
8. An air distributor for liquid fuel burners of the character set forth comprising a central structural element, a top secured to the upper end of said element and extending outwardly horizontally therefrom and thence downwardly to provide a substantially cylindrical part beyond which its peripheral portion is formed to provide a dip and an upwardly bulged portion therebeyond, a tube having its upper end fitted within and secured to the cylindrical part of the top, an annular flame spreader
9. An air distributor for liquid fuel burners of the character set forth comprising a central tubular structural element that is open at its lower end and closed at its upper end, a top secured to the upper end of said element and extending outwardly horizontally therefrom and thence downwardly to provide a substantially cylindrical part beyond which its peripheral portion is formed to provide a dip and an upwardly bulged portion therebeyond, a tube having its upper end fitted within and secured to the cylindrical part of the top, an annular flame spreader flange having its inner edge portion fitted about and secured to the tube, said flange being spaced a distance below the peripheral portion of the top and so shaped and positioned with respect thereto as to provide therewith restricted annular passageways that are spaced at different distances outwardly from the tube, the tube and the central element having circumferentially disposed series of openings in substantially the transverse plane of said passageways secured to the lower end of the tube in spaced relation to the flame spreader flange.
10. An air distributor for liquid fuel burners of the character set forth comprising a central tubular structural element that is open at its lower end, a top applied to the upper end of the tubular element and extending outwardly therefrom and thence downwardly to provide a cylindrical part that is substantially concentric with the central structural element, the peripheral portion of the top extending outwardly in a substantially horizontal direction from the aforesaid cylindrical part and thence downwardly to provide a dip beyond which said peripheral portion is curved upwardly and thence downwardly, the horizontal portions of the top and the curved edge portion of the top being provided with air openings, a tube having its upper end fitted within and secured to the cylindrical part of the top and depending to substantially the plane of the lower end of the central element, a flame spreader flange secured to and extended outwardly from the tubular element in spaced relation to the peripheral portion

of the top, and a flame spreader body surrounding the lower portion of the tube and secured thereto in spaced relation to the flame spreader flange, the central structural element and tube having series of openings in substantially the transverse plane of the space between the peripheral portion of the top and aforesaid flange.

11. In an air distributor for liquid fuel burners of the character set forth, the combination of a supporting member, a flame spreader flange extending outwardly from said member, and a flame spreader body surrounding the lower portion of the member below said flange, said body comprising a peripheral wall that is enlarged at its lower end, and a bottom wall for said body that is formed at its inner edge for application to the supporting member and at its outer edge to embrace and interlock with the enlarged lower end of the peripheral wall, the peripheral wall having a series of perforations above its enlarged lower end and said bottom having air openings.

12. In an air distributor for liquid fuel burners of the character set forth, the combination of a supporting member, a flame spreader flange carried by and extending outwardly from said member, and a flame spreader body surrounding said member in spaced relation to the flange, said body comprising a peripheral wall that is enlarged throughout its lower portion to provide an intermediate shoulder, and a bottom wall for said body that is inclined inwardly and downwardly and is formed adjacent its inner edge to fit about the lower end of the supporting member to which it is secured, the outer edge portion of the bottom wall being formed to provide an annular bead whereon the lower edge portion of the peripheral wall seats and beyond which it is flanged upwardly and inwardly to embrace the shoulder of the peripheral wall thereby to bind the parts together, the bottom wall having air openings and the peripheral wall a series of perforations above said shoulder.

13. In combination with a burner of the class described, including inner and outer wick tubes and a supporting spanner situ-

ated within the inner wick tube and spaced downwardly from the upper end thereof, the edge portion of the spanner being spaced from the inner tube to provide an air passage, and having its central portion provided with air openings, and an air distributor adapted to repose within the upper end of the burner and rest upon said spanner, said distributor comprising a central tubular element, a top applied to the upper end of the element and extending outwardly therefrom, a tube depending from the top in concentric relation to the tubular element and between the same and the edge portion of the top, a flange carried by and extending outwardly from the tube in spaced relation to said edge portion of the top, and a body surrounding the lower end of the tube and spaced below the flange, said body comprising a peripheral wall that is flanged inwardly at its upper end and enlarged at its lower end to provide an intermediate shoulder, and an annular bottom wall that is formed at its inner edge with a flange that fits and is secured to, the lower end of the tube, the bottom being provided at its outer edge with an annular depressed bead into which the lower edge of the peripheral wall of the body engages and beyond such bead with an upwardly extending flange that is turned inwardly at its upper edge above said shoulder thereby to bind the peripheral wall and the bottom wall of the body together, the bead of the bottom wall forming a seat for engagement with the spanner, and the outer flange of the bottom wall being of lesser diameter than the internal diameter of the inner wick tube whereby a space is provided between said flange and said tube in register with the aforesaid air passage, the bottom wall having air openings and the peripheral wall being provided with a series of apertures above said shoulder, while the aforesaid tube is provided with series of air openings in the plane of the space between the peripheral portion of the top and the flange and in the plane of said body.

In testimony whereof, I hereunto affix my signature.

LEE S. CHADWICK.
